DESIGN FOR A BEVERAGE MIXER RECEPTACLE

Arley U. Hook, Fostoria, Ohio, assignor to Ber-
sted Manufacturing Company, Fostoria, Ohio,
a corporation of Ohio

Application March 28, 1939, Serial No. 83,884

Term of patent 7 years

To all whom it may concern:

Be it known that I, Arley U. Hook, a citizen of the United States and resident of Fostoria, in the county of Seneca and State of Ohio, have invented a new, original, and ornamental Design for a Beverage Mixer Receptacle, of which the following is a specification, reference being had to the accompanying drawing, forming a part thereof.

Fig. 1 is a perspective view of a beverage mixer receptacle showing my new design, and Fig. 2 is a top plan view thereof.

I claim:

The ornamental design for a beverage mixer receptacle, substantially as shown.

ARLEY U. HOOK.
